SIGNAL-COUPING STRUCTURE

Henry J. Riblet, Wellesley Hills, Mass., assignor
to Raytheon Manufacturing Company, New-
ton, Mass., a corporation of Delaware

Application November 4, 1950, Serial No. 194,136

7 Claims. (Cl. 333—10)

1

This invention relates to signal-coupling structures, and more particularly to directional signal-coupling structures having a very high directivity. It is known that, if two signal channels, for example, wave guides, are suitably coupled together, for example, by being placed at right angles to each other with crossed slots appropriately positioned in their adjacent walls, energy which is being propagated in one direction in one of the guides will be fed through the slots and be propagated in the other guide in substantially one direction only.

This invention discloses a structure whereby the directivity of the directional coupling may be increased. Furthermore, it discloses a structure whereby energy propagated in a wave guide may be fed to a plurality of different wave guides, and each may then feed a common or separate load.

Briefly, the invention comprises a first wave guide having a second and a third wave guide positioned, respectively, adjacent opposite walls of said first wave guide, and substantially at right angles thereto. The axes of the second and third wave guides are displaced by substantially a quarter wave length of the signal frequency being used along the axis of the first wave guide.

Energy is directionally coupled from the first wave guide into the second and third wave guides, respectively, by crossed slot coup'ers. The slots are so positioned that energy is coupled substantially in the same direction in the second and third guides.

The minor amount of energy which is propagated in the opposite direction in the second and third guides is coupled into a fourth guide positioned at right angles to said second and third guides, and substantially parallel to said first guide. The coupling means between the second and third guides and the fourth guide comprise slots positioned parallel to the axis of the fourth guide, and substantially in the centers of the walls of the second and third guides, respectively, which are adjacent the fourth guide and near the edge of the walls of the fourth guide.

Since the slots in the two guides are substantially a quarter of a wave length apart along the axis of the fourth guide, and since energy propagated in the second and third guides are substantially ninety degrees out of phase, energy propagated from the slots in the second and third guides into the fourth guide will substantially add in one direction, and cancel in the other, thus producing directional coupling in the fourth guide.

Other and further advantages of the invention

2

will be apparent as the description thereof progresses, reference being had to the accompanying drawing, wherein:

Fig. 1 illustrates a partially, broken away perspective view of a wave guide structure embodying this invention;

Fig. 2 illustrates a cross-sectional view of the slot couplings between the first guide and the second and third guides, respectively; and

Fig. 3 illustrates a cross-sectional view of the slot couplings between the second and third guides and the fourth guide, respectively.

Referring now to Figs. 1, 2 and 3, there is shown a first wave guide 10, which is shown here as rectangular in form, having wide upper and lower sides 11 and 12, respectively, and narrow vertical sides 13 and 14, respectively. Positioned above guide 10 and at right angles thereto, is a second guide 15 having upper and lower wide sides

16 and 17, respectively, and narrow vertical sides 18 and 19, respectively. The upper side 11 of guide 10, and the lower side 17 of guide 15 are in contact, and have a pair of crossed slots 20 and 21 cut through both walls 11 and 17. Slot 20 is parallel to the axis of guide 10, and slot 21 is parallel to the axis of guide 15. Said slots intersect substantially at their mid points, and the point of intersection lies substantially on a diagonal line of the square contacting area between the walls 11 and 17.

Positioned below wave guide 10 is a third wave guide 22 having upper and lower wide sides 23 and 24, respectively, and narrow vertical sides 25 and 26, respectively. The axis of guide 22 is substantially parallel to the guide 15, and is displaced by substantially a quarter wave length of the signal frequency used along the axis of wave guide 10. The upper wall 23 of guide 22 and the lower wall 12 of guide 10 are in contact, and have a pair of crossed slots 27 and 28 cut through the walls thereof. Slots 27 and 28 are positioned in the same manner as the corresponding slots 20 and 21 between guide 10 and guide 15.

With this structure, if a wave is propagated down guide 10 from one end, for example, as shown by arrow 29, it will be coupled through slots 20 and 21 and 27 and 28 into guides 15 and 22, respectively, and will be propagated, to a large degree, in one direction in guides 22 and 15, for example, as shown by arrows 30 and 31, respectively. These outputs of guides 15 and 22 will contain substantially equal amounts of power, and may be used to feed dual loads such as, for example, dual-radiating elements of an antenna,

or the two halves of a balanced modulator or detector.

A small portion of the energy propagated in guides 15 and 22 will travel in the opposite direction in said guides, the proportion of the total energy which this smaller amount comprises being determined by the degree of directivity of the cross-slotted couplings.

A large portion of this energy is then directly coupled into a fourth wave guide 32 in the following manner. Wave guide 32 is positioned between wave guides 15 and 22, and has an upper wide side 33 in contact with the side 17, and a lower wide side 34 in contact with side 23 of guide 22. Guide 32 also has narrow vertical sides 35 and 36, respectively. The axis of guide 32 is substantially parallel to the axis of guide 10, and hence substantially perpendicular to the axes of guides 15 and 22. A slot 37 is positioned in the walls 17 and 33, slot 37 being parallel to the axis of guide 32 and adjacent vertical wall 36. Slot 37 is also positioned substantially symmetrically on the other side of the axis of guide 10. A corresponding similar slot 38 is cut in the wall 34 of guide 32 and the wall 23 of guide 22. Slots 37 and 38 will couple energy from guides 15 and 22 into guide 32.

Since the energy propagated in guide 22 lags the energy propagated in guide 15 by substantially ninety degrees when the input energy to guide 10 is in the direction of arrow 29, and since slot 38 is substantially ninety electrical degrees displaced from slot 37 along guide 32, energy propagated by slot 38 in the direction of slot 37 will substantially cancel out energy propagated in the same direction by slot 37, while energy propagated in the opposite direction by slots 37 and 38 in guide 32 will add up, producing substantially complete propagation in the guide 32 in one direction, as indicated by arrow 39. Thus, it may be seen that very little energy will be propagated in the opposite direction from arrow 39, and hence the overall directivity of this structure is very high.

The output from guide 32 along arrow 39 may be fed to a third load, such as a wave-sampling structure, and will indicate a proportional amount of the energy being fed to the loads in the direction of arrows 30 and 31. If desired, an even smaller portion of the energy fed to the loads by arrows 30 and 31 may be indicated by measuring the output in the opposite direction along guide 32. This structure could also be used with a duplexer arrangement in any of the transmit received systems where directional coupling is required.

This completes the description of the embodiment of the invention illustrated herein. However, many modifications thereof will be apparent to persons skilled in the art without departing from the spirit and scope of this invention. For example, other coupling structures than the crossed slots could be used, and other types of guides other than rectangular wave guides could be used. Indeed, coaxial cables could be used, if desired. Therefore, it is desired that this invention be not limited to the particular details of the embodiment described herein, except as defined by the appended claims.

In the claims that follow, the term "directional coupler" shall be understood to mean a device consisting of a first, or main, electromagnetic wave transmission line and a second, or auxiliary, electromagnetic wave transmission line, each line having two ends, or terminals, the lines being

coupled together at a point, or points, intermediate the ends of each, which when there exist waves traveling in both directions in the main line, delivers to one end of the auxiliary line a voltage which is largely a function of the amplitude of the wave going in one preferred direction in the main line, and relatively independent of the wave going in the opposite direction in the main line.

What is claimed is:

1. A signal-coupling structure comprising a first signal channel, a second signal channel and a third signal channel, respectively, coupled to said first channel through directional couplers, said second and third channels being, respectively, coupled to a fourth channel, the points of coupling of said second and third channels to said fourth channel being substantially a quarter wave length apart along said fourth channel at the frequency of said signal, and the points of coupling of said second and third channels to said first channel being substantially a quarter wave length apart along said first channel at said frequency.

2. A signal-coupling structure comprising a first signal channel, a second signal channel and a third signal channel, respectively, coupled to said first channel through directional couplers, said second and third channels being, respectively, coupled to a fourth channel, the points of coupling of said second and third channels to said fourth channel being substantially a quarter wave length apart along said fourth channel at the frequency of said signal, the wave length distance between the coupling of said first channel to said second channel, and the wave length distance between points of said coupling in said second channel being substantially equal to the wave length distance between corresponding points of coupling in said third channel, and the points of coupling of said second and third channels to said first channel being substantially a quarter wave length apart along said first channel at said frequency.

3. A signal-coupling structure comprising a first wave guide, a second wave guide and a third wave guide, respectively, coupled to said first wave guide through directional couplers, said second and third wave guides being, respectively, coupled to a fourth wave guide, and the points of coupling of said second and third wave guides to said fourth wave guide being substantially a quarter wave length apart along said fourth wave guide at the frequency of said signal.

4. A signal-coupling structure comprising a first wave guide, a second wave guide and a third wave guide, respectively, coupled to said first wave guide through directional couplers, said second and third wave guides being, respectively, coupled to a fourth wave guide, the points of coupling of said second and third wave guides to said fourth wave guide being substantially a quarter wave length apart along said fourth wave guide at the frequency of said signal, and the points of coupling of said second and third wave guides to said first wave guide being substantially a quarter wave length apart along said first wave guide at said frequency.

5. A signal-coupling structure comprising a first wave guide, a second wave guide and a third wave guide, respectively, coupled to said first wave guide through directional couplers, said second and third wave guides being, respectively, coupled to a fourth wave guide, the points of coupling of said second and third wave guides to

said fourth wave guide being substantially a quarter wave length apart along said fourth wave guide at the frequency of said signal, the wave length distance between the coupling of said first wave guide to said second wave guide, and the wave length distance between points of said coupling in said second wave guide being substantially equal to the wave length distance between corresponding points of coupling in said third wave guide, and the points of coupling of said second and third wave guides to said first wave guide being substantially a quarter wave length apart along said first wave guide at said frequency.

6. A signal-coupling structure comprising a first signal channel, a second signal channel and a third signal channel, respectively, coupled to said first channel through directional couplers, said second and third channels being, respectively, coupled to a fourth channel, and the points of coupling of said second and third channels to said fourth channel being substantially a quarter wave length apart along said fourth channel at the frequency of said signal.

7. A signal-coupling structure comprising a first wave guide, a second wave guide and a third wave guide, respectively, coupled to said first wave guide through directional couplers comprising a pair of crossed slots, said second and third wave guides being, respectively, coupled to a fourth wave guide, and the points of coupling of said second and third wave guides to said fourth wave guide being substantially a quarter wave length apart along said fourth wave guide at the frequency of said signal.
